BRAKE SHOE

Filed March 18, 1929

Inventor:
Robert B. Pogue
By Wm. J. Bell, Atty.

UNITED STATES PATENT OFFICE

ROBERT B. POGUE, OF CHICAGO, ILLINOIS, ASSIGNOR TO THE AMERICAN BRAKE SHOE & FOUNDRY COMPANY, OF WILMINGTON, DELAWARE, A CORPORATION OF DELAWARE

BRAKE SHOE

Application filed March 18, 1929. Serial No. 247,819.

This invention relates to railway brake shoes of the type having a ductile metal back and its object is to provide a strong and substantial anchorage of the body of the shoe to the metal back to hold the body securely to the back and to prevent parts of the body from falling away in case of fracture.

A further object of the invention is to provide a strong and rigid back which will resist tendency to straighten or flatten out in event of fracture of the body and will maintain the fractured body in serviceable condition and prevent the parts thereof from falling away.

15 And a further object of the invention is to provide a simple means for securely anchoring the ends of the body to the back plate.

In the accompanying drawings I have selected a locomotive shoe for illustrating the 20 invention and, referring thereto,

Fig. 1 is a side elevation,

Fig. 2 is a top plan view, and

Fig. 3 is a sectional view on the line 3—3 of Fig. 2.

25 Referring to the drawings, 5 is the body, 6 is the back plate and 7 is the attaching lug, these parts being, in general form and construction, well known in the brake shoe art. The body may be made of cast iron, with or without chilled portions or with inserts 8.

The back plate and the lug are preferably made of steel and the plate is provided with openings into which the body metal flows during the casting operation to embed the 30 back plate in the body to form the back thereof. The lug is engaged with the back plate and embedded in the body in any suitable manner to secure it to the body.

35 The shoe is of the flanged type and the back plate is made accordingly to cover the flanged as well as the flat part of the body. The flanged side edge 9 of the plate is embedded in the body and the opposite side edge 10 of the plate is bent downward and 40 is embedded in the body. The openings 13 in the flanged part of the plate are arranged in two series on opposite sides of a medial plane passing through the flanged part of the shoe and extending perpendicularly to the axis of the wheel with which the shoe is

adapted to be used, the openings in each series being spaced apart and staggered with relation to the openings in the other series, except at the ends of the flange where the openings are opposite. The openings in one series in the flange do not overlap the openings in the other series and this leaves a continuous unbroken portion 12 between the two series of strips extending throughout the length of the flange of the back which stiffens the back and adds to its rigidity. This is a feature of importance in my invention because it helps to prevent the back from straightening or flattening during service when the body fractures and, in this way, helps to hold the fractured parts of the body together so that the shoe can continue in service and give efficient braking. It is well known that when the body of a shoe fractures the tendency during service of the shoe is for the back to straighten or flatten, thereby opening up the cracks in the body and making the shoe less efficient in braking effect and the anchorage of the body portions to the back less effective and more liable to break away from the back. But, if the normal rigidity of the back can be maintained after the body is fractured, the parts of the body will be held together in substantially the position they occupied in the body before it was fractured, thereby maintaining the braking and anchoring efficiency.

45 The openings 13 are radially disposed to the center of the arcuate flange of the back and the walls of the openings are beveled at the sides of the openings longitudinally of the back so that the body metal is buttoned in the openings and is thereby securely anchored to the back. The openings are punched in a blank plate and the arcuate flange on the plate is formed which inclines the side walls of the openings longitudinally of the plate with respect to each other to cause the body metal to form a button 11 in the openings during the casting operation. The plate is also provided with a series of openings 16 adjacent the side edge 10 and these openings are arranged in substantial alinement and extend through the corner 15 of the plate and partly in the flat portion of the plate and

partly in the downturned marginal portion 10 of the plate. These holes are also stamped before the plate is shaped and, bending the marginal portion 10 downward into a flange as shown, has the effect of inclining the side walls of the openings 16 longitudinally of the back to also produce buttons 14 on the body when the body metal solidifies in the casting operation. This buttoning of the body to the back at the flange and at the opposite edge of the shoe is highly important in providing a permanent anchorage of the body to the back, and it also has the effect of increasing the rigidity of the back and maintaining the general shape and contour of the shoe.

I provide a plurality of openings 17 arranged in substantial alignment transversely of the flat portion of the back at the end of the shoe to receive the body metal and to anchor 20 the ends of the body to the ends of the back. It is found in practice that this method of anchoring the body to the back at the ends of the shoe is especially efficient; it provides a much larger area of connecting metal between 25 the end stops 18 on the back of the shoe and the body of the shoe than has been customary heretofore and this enlarged connecting area is divided in such a way that strength and rigidity of the back is not impaired at this 30 portion of the back, and the anchoring of the end stops to the body and of the body and end stops to the back is made more substantial and efficient. I also provide a plurality of openings 19 in the flat portion of the back plate 35 between the arcuate flange and the downturned flange and these openings may be elongated, as shown, or in any other desired shape.

My invention provides a brake shoe of 40 strong and substantial construction in which the body is securely anchored at and between its ends to the back plate so that in event of fracture of the body the parts thereof will be securely held together and the shoe will be maintained in serviceable and efficient condition. The arrangement of the openings in the 45 arcuate flange and in the corner of the plate formed by the downturned flange is important because of the efficient anchorage afforded, and the arrangement of the two series of 50 openings in the arcuate flange on opposite sides of a continuous unbroken strip, with the openings staggered between the end portions of the plate, is important because of the added anchoring effect without impairing the rigidity of the plate.

Changes in the form, construction and arrangement of parts of the invention may be made to adapt it for different sizes and shapes of shoes, or to meet other conditions, and I 60 reserve the right to make all such changes as fairly fall within the scope of the following claims.

I claim:

1. A flanged brake shoe adapted for cooperation with a wheel and comprising a body

and a plate embedded in the back thereof, the plate having an arcuate flange on the flanged part of the body, and said flanged part of the plate having two series of spaced openings located respectively on opposite sides of a 70 medial plane passing through said flanged part of the body and extending perpendicularly to the axis of the wheel.

2. A flanged brake shoe comprising a body and a plate embedded in the back thereof, the plate having an arcuate flange on the flanged part of the body and a downturned flange at its opposite marginal edge, the arcuate flanged part of the plate having two series of spaced openings located on opposite sides of 80 an integral, continuous and unbroken centrally disposed longitudinal strip portion, and the opposite flanged portion of the plate having a series of openings extending through the corner of the plate formed by said flange, 85 the body metal extending into all of said openings and having a button anchor therein.
